UNITED STATES PATENT OFFICE.

GUSTAV F. W. SCHULTZE, OF OAKLAND, CALIFORNIA.

COIN-CONTROLLED MECHANISM.

1,090,945.

Specification of Letters Patent. Patented Mar. 24, 1914.

Application filed September 6, 1912. Serial No. 718,970.

To all whom it may concern:

Be it known that I, GUSTAV F. W. SCHULTZE, a citizen of the United States, residing at Oakland, in the county of Alameda and State of California, have invented 5 certain new and useful Improvements in Coin-Controlled Mechanism, of which the following is a specification.

The hereinafter described invention relates to means for regulating the return of 10 a deposited coin or token to the depositor thereof within a coin actuated device, or the retention thereof within the machine as a compensation for the value given therefor, 15 the construction and operation of the working parts being such that the user of the machine is given an opportunity to have returned the deposited coin or token, depending on the choice or selection as to the coin 20 opening into which the coin for throwing into operation the actuating mechanism is deposited; the object of the invention being to create an interest and attract attention to the coin controlled machine and by so doing 25 causing a greater number of persons to use the machine than otherwise would be the case.

The invention is adapted for use in connection with any form of a coin controlled 30 machine, but for the purpose of illustration the same is disclosed as applied to an ordinary coin actuated weighing machine, wherein a charge is usually made for giving the weight of the user thereof. Usually, the 35 user of such devices deposits a coin or token and in return is given his weight, the coin being retained within the machine as payment therefor, or in case of a coin controlled vending apparatus a given quantity 40 of merchandise is discharged from the machine in consideration of the deposited coin or token.

In the present case the user of the machine is given a choice of a plurality of deposit 45 openings in which to place the actuating coin or token. Should the selection of an opening for the deposit of the coin or token be the one controlling the return thereof, the deposited coin or token is directed to the exterior 50 of the machine for the recovery thereof and in such an event the user is dispensed that value which is controlled by the apparatus and in addition has returned the coin or token deposited for actuating the machine. 55 In the case of a weighing scale, the weight

of the user is given and the deposited coin returned and in the case of a vending machine the merchandise controlled thereby is discharged and the coin or token returned. In either event, the return of the coin or token to the user of the machine, or the retention thereof within the machine is dependent solely on the selection by the user as to the opening for the deposit of the coin, the return of the coin, or the retention thereof within the machine being solely governed by the position of the actuating mechanism of the machine when the coin or token is deposited by the user thereof.

Heretofore, the return of the deposited coin or token from within a coin controlled weighing machine has been dependent upon the registry of a guess by the user as to the weight, the return of the coin being dependent on the coincident of the registered guess 70 with the weight disclosed by the scale mechanism, but such a constructed machine is exceedingly complex in its construction, requires extreme nicety as to regulation, and requires that the user thereof make a registry as to his weight. Such mechanism is entirely dispensed with under the present invention, and the same is applicable to all forms of coin controlled and coin actuated 75 machines, and by the expression coin controlled machine, as hereinafter employed, is meant to be understood any form of a coin controlled apparatus.

With the above mentioned and other objects in view, the invention consists in the 80 novel construction and combination of parts, hereinafter described, illustrated in the accompanying drawings, and pointed out in the claims hereto appended; it being understood that various changes in the form, proportion, size and minor details of construction 85 may be resorted to without departing from the spirit or sacrificing any of the advantages of the invention.

To comprehend the invention reference 90 should be had to the accompanying drawings, wherein is disclosed one form of my invention, and in which the same is illustrated as applied to a weighing apparatus.

Figure 1 is a side elevation of a spring 105 scale, the upper portion of which is in vertical section, disclosing the scale mechanism and the mechanism controlled by the operation of the scale for directing the disposal of a deposited coin for releasing the lock 110

mechanism of the weighing machine or scale. Fig. 2 is a sectional view on line 2—2, Fig. 1 of the drawings, and viewed in the direction of the arrow, disclosing the coin chutes 5 or runways terminating at their lower ends into delivery channels, the pivoted directing plate for controlling the delivery openings for the deposited coin, the electrically controlled operating means for the same, and 10 the arms carried by the platform operated bar, for restoring the directing plates to their normal position. Fig. 3 is a broken sectional view of the upper portion of the scale casing with the weighing mechanism 15 removed, disclosing the coin receiving slots and contact mechanism operated upon the depositing of a coin for directing the disposal of the coin. Fig. 4 is a vertical sectional view of the scale casing viewed from 20 the rear disclosing the weighing mechanism and the coin operated controlling means for the same. Fig. 5 is a view of the controlling circuit for the device.

Referring more particularly to the drawings, the reference numeral 1 designates a suitable scale base on the forward portion of which is mounted the scale platform 2, and from the rear of the base extends the vertical casing 3, in which is mounted the 30 operating mechanism of the scale.

The weight indicating mechanism of the scale is constructed in the following manner: Extending vertically within the casing 3 is a scale rod 4, connected at its lower end 25 to the platform mechanism and carrying at its upper end a transverse bar 5, connected at each end to suitable coiled springs 6, suspended at their opposite ends from a suitable bar 7, supported by the interior side 35 walls of the casing 3. Slidably mounted in suitable guides 8 formed in a plate 9, attached to the interior of the front wall of the casing 3 in rear of a dial opening 10, adapted to be inclosed by a glass 11, is a bar 40 12, the lower end of which rests on the transverse bar 5 and the upper end of which is provided on one face with teeth 13, which intermesh with a pinion 14 loosely mounted 45 on a horizontal shaft 15, one end of which is journaled in the upper portion of the plate 9, and the other end is journaled in and extends through a dial plate 16 positioned in rear of the dial opening 10, and secured to the outer end of said shaft 15 50 55 between the glass 11 and the dial plate 16 is an indicating hand 17, adapted to rotate about the face of the plate 16 and indicate the weight of the user of the scale. The pinion 14 is provided on one surface with an 60 arm 18 adapted to contact with a corresponding pin 18' projecting from one surface of a disk 19, secured to the shaft 15, and mounted on the shaft adjacent the disk 19 is a grooved pulley 19' to which is fastened one end of a flexible cord 20, the oppo-

site end of which supports a suitable weight 21. Secured at its lower end to the scale rod 4, below the transverse bar 5 is a suitable rod 22 which is of sufficient length that the upper end thereof is adapted to engage a 70 plate 23, pivoted at one end to a bracket 24 and provided at its opposite end with a suitable pointed tongue 25 which is normally unseated from suitable teeth formed in the peripheral edge of the disk 19. The end 75 of the rod 22 when in engagement with the plate 23 lifts the tongue 25 thereof, from the teeth in the edge of the disk 19, but should a person step on the scale platform, the rod 22 will be pulled downwardly with the bar 80 4 and the tongue 25 will fall into engagement with the ratchets and prevent the lower end of the bar 12 from following the scale rod downwardly, until such time as a coin 85 is inserted in the machine.

The coin operated releasing mechanism is preferably constructed in the following manner: Formed in the front wall of the casing 3 and arranged one at either side of the dial opening 10 are downwardly and inwardly inclined coin receiving slots 26, at the inner ends of which are positioned coin receiving cups 27, open at their outer side as at 28, and said cups are secured to the ends of suitable rods 29 and 29' pivoted at 30 90 95 adjacent the plate 23, and said rods are provided with fingers 31 adapted to extend under the plate 23. The rods are also provided with weighted arms 32 which extend over the plate 23 and the weights of said arms 100 are sufficient to maintain the cups 27, carried at the opposite ends of the rods, in position to receive a coin from the slots 26.

From the above construction, it will be observed that when a person steps on the 105 scale platform, that the scale bar 4 will be drawn downwardly against the tension of the springs 6, and by the operator inserting a coin in either slot, the same will be received within one of the cups and the weight of the coin will over-balance the weighted arms 32, and the fingers 31 in their upward movement will lift the plate 23 upwardly and remove the tongue 25 thereof from the notches in the disk 19, and the weight of the bar 12, which is greater than the weight 21, will drop until it rests on the scale bar 4, the dropping of the bar 12 will rotate the pinion 14, which through the arm 18 and pin 18', which is carried by 110 the disk 19 secured to the shaft 15, will rotate the hand 17 about the dial 16, and the weight of the user of the scale will be indicated thereby, and after the coin drops from the open side 28 of the cup in which it is 115 deposited, the weighted arm 32 will restore the cup to its normal position, the finger 31 will disengage from the plate 23, and the tongue 25 thereof will drop into the teeth in the disk 19 and lock the shaft 15 to which 120 125 130

said disk is secured against rotation. Upon the operator stepping off of the platform 2, the springs 6 will draw the scale rod 4 upwardly, elevating the bar 12 and rotating the pinion 14, and in this movement the arm 18 will disengage from the pin 18' and the pinion will be returned to its normal position. As the scale bar 4 reaches its highest position, the rod 22 carried by the scale bar 10 will engage the plate 23, elevate the tongue 25 carried thereby from engagement with the teeth on the disk 19, and the action of the flexible connection 20 and weight 21 will rotate the shaft 15 and the indicating hand 17 15 will be restored to its normal position.

Associated with and positioned below each of the coin cups 27 to receive the deposited coin, when the same rolls from the open side 28 of the cup, are guideways 33, 20 each divided at their lower ends by a wall 34 into two channels 35 and 36, the channels 35 leading to the interior of the casing 3, and the channels 36 provided at their lower ends with a chute 37 which extends through 25 the side wall of the housing and leads to the exterior thereof. Within each coin channel or chute is located a directing plate 38, each being mounted on a shaft 39 journaled in the side walls of the said channels immediately above the walls 34 and the said shafts 39 are each provided at one of their ends with weighted trip fingers 40, which are each adapted to be normally supported in a horizontal position by armatures 40' and 41, 35 associated with electro-magnets 42 and 43, which are operated in a hereinafter described manner. The directing plates 38 when in their normal positions and when the trip fingers 40 are in their normal positions are adapted to close the channels 36 and direct the coin into the interior of the casing 3, and when the fingers are tripped the weight of the trip fingers will cause the directing plates to pivot, shutting off the 40 channels 35 and opening the channels 36 which will direct the coin out through the chute 37.

The mechanism for controlling the disposal of the coin after being inserted in the 50 receiving slots is constructed in the following manner: Mounted to reciprocate in guides in the rear of the casing 3 is a vertically extending rod 44, provided on one face with an inwardly spring pressed pawl 45, 55 which is adapted to engage a suitable ratchet disk 46 secured to a shaft 47 which is rotatably mounted in a plate 48. The shaft 47 is provided exteriorly of the plate 48 with a suitable disk 49, of non-conducting material, and carried by said plate are contact plates 50 from which extend to the shaft 47 suitable leads, and said plates are adapted to contact with fingers 51 and 52 60 positioned at diametrically opposite sides of the disk and from which extend suitable

leads hereinafter more fully described. A star wheel 53 is keyed to rotate with the shaft 47, and cooperating with said star wheel is a spring arm 54, and the points on said wheel are so arranged that the spring 70 arm 54 will engage the same when rotated to position one of said contact plates in engagement with one of the contact fingers 51 or 52. The lower end of the rod 44 rests on the free end of a lever 53', pivoted, as at 75 54', to a bracket, and said lever rests on a pin 55 projecting from the shaft 4, and when the scale platform is unoccupied, the shaft 4 forces the lever 53' upwardly, which retains the rod 44 in the position disclosed 80 in Fig. 1. When the scale platform is occupied, it will be observed that the lever 53' will move downwardly with the rod 4 and that the rod 44 will drop by gravity, the pawl 45 carried thereby rotating the disk 85 49 to present a new contact plate to the finger 51 or 52. The trip fingers 40 after being tripped are restored to their normal position by suitable arms 56 secured to the rod 4 and which operate against projections 90 57 and 58 secured to the shafts 39 at the opposite ends thereof from the trip fingers 40.

The circuit for controlling the disposal of the coin is as follows: Contact plates 59 are adapted to be engaged by each of the 95 rods 29 when the same are in their downwardly inclined position, said plates are connected by a lead 60, and from one of said plates extends a lead 61 which is connected to a battery 62. A lead 63 extends from 100 the battery 62 and is connected to the electro-magnets 42 and 43, and said magnets are connected by the respective leads 64 and 65 to the contact fingers 51 and 52. The shaft 47 is connected to the arms 29 by suitable 105 leads 65 and 66.

The operation of the circuit is as follows: Assuming that the disk carrying the contact points 50 is in the position as in Fig. 5, and a coin is inserted in the cup 27 carried 110 by the rod 29', the rod in its downward movement will make contact with the plate 59, and a circuit will be formed through the leads 60 and 61, battery 62, lead 63, electro-magnet 43, lead 65', finger 52, plate 50 115 and lead 66; and as the above circuit is made the armature 41 will be drawn from under the trip finger 40 and the directing plate associated therewith will be thrown to close the channel 35 leading into the casing 120 and the coin thus deposited will be directed through the channel 36 into the chute 37. Should a coin be inserted in the cup 27 carried by the arm 29 when the parts are positioned as in Fig. 5, the circuit will not 125 be completed, as the finger 51 is not resting on a contact plate 50 and the coin will be directed into the interior of the casing 3. The return of the coin deposited to the user of the scale or the retention thereof within 130

the scale is dependent solely as to which of the coin slots the user selects for the deposit of the coin.

Having thus fully described my invention what is claimed as new and is desired to be protected by Letters Patent is:—

1. In a coin actuated machine, the combination with a casing provided with a plurality of coin receiving openings and coin discharge means, weight indicating mechanism situated within the casing, and means thrown into action upon the deposit of a coin within one of said receiving openings for releasing the weight-indicating mechanism and for controlling the discharge of the actuating coin from within the casing or the retention thereof within the casing in accordance with the receiving opening within which the same is deposited.
2. In a coin actuated weighing machine, the combination with a casing provided with a plurality of coin receiving openings and coin discharge outlets, coin runways extended from said receiving openings and adapted to communicate with said discharge outlets, weight-indicating mechanism situated within the casing, means interposed between the coin runways and the coin discharge outlets for controlling the communication therewith, and means thrown into action by the weight of a deposited coin within one of said receiving openings for releasing the weight-indicating mechanism and for actuating the means interposed between the coin runways and the coin discharge outlets for controlling the discharge of the actuating coin from within the casing or the retention thereof within the casing, in accordance with the receiving opening within which the same is deposited.
3. In a coin actuated machine, the combination with a casing provided with a plurality of coin receiving openings and coin discharge outlets, a coin actuated weight-indicating mechanism situated within the casing, and means thrown into operation on the deposit of a coin for releasing the weight indicating mechanism for controlling the discharge of the actuating coin from within the casing through the discharge outlets or the retention thereof within the casing in accordance with the receiving opening within which the same is deposited.
4. In a coin actuated machine, the combination with a casing provided with a plurality of coin receiving openings and coin discharge devices, a coin runway extended from each of said receiving openings and adapted to communicate with said discharge

devices, means interposed between each coin runway and the discharge devices for controlling the communication therewith, coin controlled weight-indicating mechanism situated within the casing, and means thrown into action upon the deposit of a coin within either of said receiving openings for releasing the said weight-indicating mechanism and for actuating the means interposed between each coin runway and the corresponding discharge device dependent upon the receiving opening within which the actuating coin is deposited, for controlling the discharge of the actuating coin or token from within the casing through the discharge device or the retention thereof within the casing.

5. In a coin actuating machine, the combination with a casing provided with a plurality of coin receiving openings, and a plurality of coin discharge outlets, and coin runway extended from each of said receiving openings and adapted to communicate with the discharge outlets, weight indicating mechanism situated within the casing; devices for releasing the weight indicating mechanism upon the insertion of a coin in either of said receiving openings, devices within the runways for controlling the discharge of the actuating coin or token from within the same, and electrically operated means for actuating said devices to govern the travel of the said coin.

6. In a coin actuated machine, the combination with a casing provided with a plurality of coin receiving openings and coin discharge outlets, coin runways extended from said receiving openings and adapted to communicate with said discharge outlets, a weight indicating mechanism situated within said casing and released upon the insertion of a coin in either of said receiving outlets, and mechanism interposed between said coin runways and the discharge outlets for controlling the communication therewith, said mechanism being capable at all times of establishing a communication with said discharge outlets upon the insertion of an actuating coin in certain of said receiving openings.

In testimony whereof I have signed my name to this specification in the presence of two subscribing witnesses.
